UNITED STATES PATENT OFFICE.

PEDER T. PEDERSON, OF WILLOW LAKE, SOUTH DAKOTA, ASSIGNOR OF ONE-HALF TO
HANS A. REKSTAD, OF WILLOW LAKE, SOUTH DAKOTA.

TOY PISTOL.

1,030,532.

Specification of Letters Patent.

Patented June 25, 1912.

Application filed April 26, 1912. Serial No. 693,495.

To all whom it may concern:

Be it known that I, PEDER T. PEDERSON, a citizen of the United States, residing at Willow Lake, in the county of Clark and 5 State of South Dakota, have invented certain new and useful Improvements in Toy Pistols; and I do hereby declare the following to be a full, clear, and exact description of the invention, such as will enable 10 others skilled in the art to which it appertains to make and use the same.

This invention relates to toy pistols for discharging peas, shot or pellets, by means of a spring; and it consists in the novel construction and combination of the parts hereinafter fully described and claimed.

In the drawings, Figure 1 is a side view of the pistol, constructed according to this invention. Fig. 2 is a plan view. Fig. 3 is 20 a front end view. Fig. 4 is a longitudinal section through the barrel taken on the line $x-x$ in Fig. 2, and showing the plunger retracted. Fig. 5 is a cross-section, taken on the line $y-y$ in Fig. 2.

The barrel 2 of the pistol is formed on or 25 secured to the front part of a frame 3. A suitable handle 4 projects downwardly from the rear end portion of the frame. The frame has a channel-shaped guide-bar 5 at 30 its lower part and the front end portion of this bar extends under the barrel and has external grooves 6 in its sides where it joins onto the barrel.

SLOTS 7 are formed in the sides of the 35 frame longitudinally of the barrel, and a longitudinal slot 8 is formed in the top of the frame. A recess 9 is formed in the lower part of the frame, and has a catch shoulder 10 at its front end where it joins onto the 40 channel-shaped guide, and 11 is the trigger which is pivoted on a pin 12 and arranged to work in the recess 9. The trigger is a small bell-crank lever, and it has a rearwardly projecting member 14 at its upper 45 part.

A plunger 15 is slidable in the barrel 2, and has a guide block 16 on its rear end. This guide block has a catch shoulder 17 on its lower front edge, and when the plun-

ger is retracted this shoulder engages with 50 the shoulder 10.

A spring 18, formed of a band or strip of india rubber, is arranged in the grooves 6 at the sides of the barrel. The front end of the spring is secured in a notch 19 at the 55 front end of the bar 5, and its rear end portion passes through the slots 7 and engages with a notch 20 in the rear end of the block 16, a little above the level of the grooves 6.

The plunger slides loosely in the barrel, 60 and it and the block are made of such a length that they can be placed in position through the slot 8 before the spring is secured in place.

The upper part of the block 16 works in 65 the slot 8, and forms a projection 21 for retracting the plunger. When the plunger is retracted by hand, the downward pull of the inclined portions of the spring causes the shoulder 17 to engage with the shoulder 10. 70 When the trigger is pulled, the part 14 raises the guide block, and disengages the shoulders, and the pea or shot is discharged from the barrel by the plunger and spring.

What I claim is:

In a toy pistol, the combination, with a 75 frame having a rectangular guide channel provided with longitudinal slots in its sides, said frame having a recess or slot extending vertically through it below the rear part of 80 the guide channel, and having also a barrel at its front end; of a plunger slidable in the barrel and having at its rear end a rectangular block which is slidable in the said guide channel and adapted to engage with 85 the upper part of the said recess, a spring band working in the said longitudinal slots and operating to propel the plunger and block, and a trigger pivoted in the said recess with its lower part projecting from the 90 bottom end thereof and adapted to release the said block.

In testimony whereof I have affixed my signature in the presence of two witnesses.

PEDER T. PEDERSON.
